KEY ARRANGEMENT FOR OFFICE MACHINES AND THE LIKE

Filed Oct. 27, 1953

Technical drawings illustrating a mechanical assembly, likely a valve or actuator, shown in five views:

- FIG. 1:** A side view of the assembly. It features a central vertical rod (4) with a circular base (3) and a handle (2) attached. A small circular component (5) is positioned between the handle and the base. The rod passes through a housing (6) which is secured to a base plate (8) via bolts (11). A cap (9) is shown attached to the top of the rod.
- FIG. 2:** A top-down view of the base plate (8). It shows a circular opening (12) with a central bolt (13) and a cross-shaped slot (14) for the handle.
- FIG. 3:** A view of the base plate (8) from the side, showing the housing (6) and the base (11) attached.
- FIG. 4:** A view of a component (9) with a central slot (10) and a side slot (15).
- FIG. 4a:** A view of a component (9) with a central slot (10) and a side slot (15), similar to FIG. 4 but with a different orientation.
- FIG. 4b:** A circular view of a component (9) with a central slot (10) and a side slot (15).

KEY ARRANGEMENT FOR OFFICE MACHINES AND THE LIKE

Arthur Beyer, Wilhelmshaven, Germany, assignor to
Olympia Werke Aktiengesellschaft, a joint-stock company

Application October 27, 1953, Serial No. 388,595

Claims priority, application Germany November 4, 1952

8 Claims. (Cl. 197—102)

The present invention relates to office machines such as calculating machines of all sorts. More particularly, the present invention relates to an arrangement for releasably mounting a key cap on a key lever of such machines.

With known office machines, the covers are generally provided with slots through which the key levers extend, and it is necessary to remove the key caps from the key levers before the machine cover can be removed. It is usually a great inconvenience to remove the key cap from the key levers because special tools are often required and because the key levers are extremely inaccessible.

One of the objects of the present invention is to overcome the above drawbacks by providing a key arrangement wherein the key caps may be easily and quickly removed from the key levers without the use of any tools whatsoever.

Another object of the present invention is to removably connect the key caps to the key levers in such a way that the key caps are securely connected to the key levers except when removed therefrom.

A further object of the present invention is to provide a releasable connection between a key cap and a key lever which also prevents turning of the key cap with respect to the key lever.

An additional object of the present invention is to provide a key arrangement capable of accomplishing all of the above objects and at the same time being made up of relatively few, simple and ruggedly constructed parts which are inexpensive to manufacture and which will give reliable service over a long period of time.

With the above objects in view the present invention mainly consists of a key arrangement for office machines and the like, this key arrangement including a key cap and the inner face of the key cap and a bottom outer face. The insert is formed with a passage extending from its inner face toward its outer face and is also formed at its outer face with a first cutout extending laterally from the passage to form a shoulder therewith. One of the above-mentioned inner faces is formed with a second cutout located opposite the first cutout and also extending laterally from the passage to form a shoulder therewith. A key lever having a springy free end portion extends through the passage of the insert, engages the shoulders thereof, and is located in the cutouts for releasably connecting the key cap to the key lever.

The novel features which are considered as characteristic for the invention are set forth in particular in the appended claims. The invention itself, however, both as to its construction and its method of operation, together with additional objects and advantages thereof, will be best understood from the following description

2

of specific embodiments when read in connection with the accompanying drawings, in which:

Fig. 1 is a fragmentary, side elevational, partly sectional view of a key arrangement constructed in accordance with the present invention;

Fig. 2 is a view of the key cap of Fig. 1 as seen from the underside thereof;

Fig. 3 is a transverse sectional view of the key cap of Fig. 1;

10 Fig. 4 is a sectional elevational view of an insert adapted to be fixed within the key cap of Figs. 2 and 3;

Fig. 4a is a sectional elevational view of the insert of Fig. 4 taken at a plane which is normal to the plane of Fig. 4; and

15 Fig. 4b is a partly sectional top plan view of the insert of Fig. 4.

Referring now to the drawings, it will be seen that a key lever 1 of an office machine has a free end portion 2, made of a springy strip of metal, which extends 20 through a slot in a machine cover which is indicated in dot-dash lines in Fig. 1. This free end portion 2 of the key lever 1 is formed with a cutout 3 extending inwardly from the extremity of end portion 2 and being enlarged at its innermost part to provide the free end portion 2 of key lever 1 with a pair of springy tongues 4 and 5 which are yieldably movable toward each other. Each tongue has an outer side edge portion distant from the other tongue and formed with a notch so as to provide each tongue with an upper shoulder 6 and a lower shoulder 7, as viewed in Fig. 1. The free end portion 2 of the key lever 1 provides the key lever with a springy means for releasably connecting the lever 1 to a key cap means.

25 This key cap means includes the key cap 8 and the insert 9. The key cap 8 is formed with a recess 11 extending inwardly from its bottom face toward its top face and having at its innermost part an inner face directed toward the bottom of the key cap 8 and formed with a groove 12 extending across this inner face of recess

30 11. The key cap 8 is also formed with a recess 13 extending inwardly from the groove 12 and communicating with the top face of key cap 8 so that this key cap may communicate at recess 13 with a spray nozzle or the like for placing the material 14, of a contrasting color with the key cap, on the top face thereof, this material 14 being provided with the indicia of the key cap.

35 The insert 9, which is preferably made of metal, is fixed to the key cap 8 and located in the recess 11 thereof. For example, the insert 9 may be press fitted in the interior of key cap 8 or it may be fixedly joined thereto by any other suitable joining means. The insert 9 has an inner, upper face located adjacent the groove 12 and is formed with a substantially cylindrical recess extending downwardly from its inner face towards the bottom face of insert 9, this insert 9 being formed in its bottom face with an elongated groove 10 communicating with the cylindrical recess of the insert so that this cylindrical recess forms a passage providing communication between grooves 10 and 12.

40 45 A pair of projections 15 extend upwardly from the upper face of insert 9, are located directly over the groove 10, and extend into the groove 12 so that the grooves 10 and 12 are parallel with each other when the projections 15 are located in the groove 12. Although projections 15 are preferred for assuring the parallel relationship between grooves 10 and 12, because these projections 15 also prevent any unforeseen turning of insert 9 with respect to key cap 8, it is also possible to omit the projections 15 and locate the groove 10 in parallel relation with groove 12 with a suitable tool when the insert 9 is fixed within the key cap 8.

The notches in the outer side edges of the springy tongues 4 and 5 have a length which is substantially equal to the length of the cylindrical recess of insert 9 so that, as is shown in Fig. 1, when the springy tongues 4 and 5 extend through the cylindrical recess of insert 9 the shoulders 6 engage the inner rim of insert 9 at the inner face thereof and are located within the groove 12, while the shoulders 7 respectively engage the shoulders formed by the junction between the groove 10 and the cylindrical recess of insert 9. In effect, the groove 12 extends transversely across the top of insert 9 to form an additional pair of shoulders with the inner upper rim thereof, these additional shoulders respectively cooperating with the shoulders 6.

It will be noted that this inner upper rim of insert 9 is rounded and that the shoulders 6 are matingly rounded so that the cap means 8, 9 may be removed from the key lever 1 simply by being pulled off from the springy key end portion 2 thereof. In order to replace the key cap means 8, 9 on the key levers 1, 2 it is only necessary to move the tongues 4 and 5 slightly toward each other so that they will enter through the groove 10 into the cylindrical recess of insert 9. Then the key cap means 8, 9 is pushed downwardly along the free end portion 2 of key lever 1 until the insert 9 snaps into the notches in the tongues 4 and 5, the parts then having the position shown in Fig. 1 where shoulders 6 and 7 of the tongues 4 and 5 are respectively located in the grooves 12 and 10 to prevent turning of cap means 8, 9 with respect to the key levers 1, 2. If desired, the upper outer corners of tongues 4 and 5 may be rounded so that these tongues will automatically move toward each other upon being pushed into insert 9, and/or the shoulders at the junctions between groove 10 and the recess of insert 9 may be rounded for the same purpose.

Although the above described construction is preferred, it is possible to extend the recess of insert 9 completely through the same so that the groove 10 would only have opposite portions located on the bottom periphery of the insert 9, and it is also possible to form the groove 12 in the top face of insert 9 rather than on the inner face of recess 11 which is directed toward the bottom of key cap 8.

It will be understood that each of the elements described above, or two or more together, may also find a useful application in other types of office machines differing from the types described above.

While the invention has been illustrated and described as embodied in a key arrangement for office machines, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A key arrangement for office machines and the like, comprising, in combination, key cap means having a bottom face formed with a notch, being formed with a passage communicating with said notch and extending from the latter toward the top face of said key cap means, and being formed in its interior with a cutout located opposite said notch and also communicating with said passage, said notch and cutout defining shoulders in said key cap means where said notch and cutout join said passage; and a key lever having a springy free end portion extending through said passage, engaging said

shoulders, and being located in said cutout and notch for releasably connecting said key cap means to said key lever.

2. A key arrangement for office machines and the like, comprising, in combination, key cap means formed in its interior with a passage extending from the bottom toward the top of said key cap means and also being formed with a pair of substantially parallel elongated cutouts respectively located at different distances from the top of said key cap means, being located opposite each other, and extending laterally from said passage to form shoulders, the lowermost of said cutouts being located at the bottom face of said key cap means; and a key lever having a springy free end portion extending through said passage, engaging said shoulders, and being located in said cutouts for releasably connecting said key cap means to said key lever.

3. A key arrangement for office machines and the like, comprising, in combination, a key cap formed with a recess extending inwardly from the bottom thereof and having at the innermost part of said recess an inner face directed toward the bottom of said key cap; an insert located in said recess and being fixed to said key cap, said insert having an inner face located adjacent said inner face of said key cap and a bottom outer face, said insert being formed with a passage extending from its inner face toward its outer face and being formed at its outer face with a first cutout communicating with and extending laterally from said passage to form a shoulder therewith, one of said inner faces being formed with a second cutout located opposite said first cutout and also extending laterally from said passage to form a shoulder therewith; and a key lever having a springy free end portion extending through said passage, engaging said shoulders, and being located in said cutouts for releasably connecting said key cap to said key lever.

4. A key arrangement for office machines and the like, comprising, in combination, a key cap formed with a recess extending inwardly from the bottom thereof and having at the innermost part of said recess an inner face directed toward the bottom of said key cap; a metal insert located in said recess and being fixed to said key cap, said insert having an inner face located adjacent said inner face of said key cap and a bottom outer face, said insert being formed with a passage extending from its inner face toward its outer face and being formed at its outer face with a first cutout communicating with and extending laterally from said passage to form a shoulder therewith, one of said inner faces being formed with a second cutout located opposite said first cutout and also extending laterally from said passage to form a shoulder therewith; and a key lever having a springy free end portion extending through said passage, engaging said shoulders, and being located in said cutouts for releasably connecting said key cap to said key lever.

5. A key arrangement for office machines and the like, comprising, in combination, a key cap formed with a recess extending inwardly from the bottom thereof and having at the innermost part of said recess an inner face directed toward the bottom of said key cap and being formed with an elongated groove; an insert located in said recess and being fixed to said key cap, said insert having an inner face located adjacent said inner face of said key cap and a bottom outer face, said insert being formed with a passage extending from its inner face toward its outer face and being formed at its outer face with an elongated cutout extending laterally from said passage to form a shoulder therewith and being substantially parallel to said groove, said passage forming a second shoulder with said inner face of said insert; and a key lever having a springy free end portion extending through said passage, engaging said shoulders, and being located in said cutout and groove for releasably connecting said key cap to said key lever.

6. A key arrangement for office machines and the like,

comprising, in combination, a key cap having a top face adapted to carry indicia and having a bottom face located opposite said top face, said key cap being formed with a recess extending inwardly from said bottom face thereof toward said top face and said key cap having at the innermost part of said recess an inner face directed toward the bottom of said key cap and formed with an elongated first groove; an insert located in said recess, being fixed to said key cap, having an inner face located adjacent said inner face of said key cap, and having an outer face located adjacent said bottom face of said key cap, said insert being formed with a substantially cylindrical recess extending from said inner face of said insert toward said outer face thereof, and said insert being formed in its outer face with an elongated second groove substantially parallel to said first groove, extending across said outer face of said insert, and communicating with said cylindrical recess to provide a pair of shoulders on said insert; and a key lever having a springy free end portion formed with a cutout extending inwardly from the extremity thereof to provide said free end portion of said key lever with a pair of springy tongues capable of being moved toward each other, each of said tongues having an outer side edge portion located distant from the other tongue and formed with a notch having a length substantially equal to the length of said cylindrical recess of said insert to provide each of said tongues with a pair of shoulders located at opposite ends of the notch thereof, said tongues extending through said cylindrical recess of said insert into said first groove, and one of the shoulders of each of said tongues engaging the rim of said insert at the junction between said inner face and recess thereof, the other shoulders of said tongues respectively engaging said shoulders of said insert at the junction between said second groove and cylindrical re-

cess, so that said key cap and key lever are removably connected to each other.

7. A key arrangement as defined in claim 6 and wherein in said one shoulder of each tongue and said rim of said insert are matingly rounded so that said key cap may be pulled off from said key lever without any tools.

8. A key arrangement for office machines and the like comprising, in combination, key cap means formed with a recess and having in said recess projections which are adapted to serve as catches, said projections having each an elongated side face extending in axial direction of said key cap means and a pair of end faces substantially normal to said side face; and a key lever having a springy free end portion formed with a cutout extending inwardly from the extremity thereof to provide said free end portion of said key lever with a pair of springy tongues capable of being moved toward each other, each of these tongues having an outer side edge portion located distant from the other tongue and formed with a notch having a length substantially equal to the length of said side faces of said projections to provide each of said tongues with shoulders located at opposite ends of the notch thereof, said tongues being located in said recess and said shoulders respectively engaging said end faces of said projections for releasably connecting said key cap means to said key lever.
